DEFLECTION TENSIOMETER

Fred B. Tamm, Bettendorf, Iowa, assignor to Bettendorf Bakery Equipment Company, Bettendorf, Iowa, a corporation of Iowa

Application January 3, 1955, Serial No. 479,563

4 Claims. (Cl. 73—144)

This invention relates to a tensiometer suitable for use in determining the tension on the individual slicer blades in a bread slicing machine.

The device of the present invention is a hand instrument that can readily be applied successively to exposed portions of the slicer blades in a bread slicing machine to determine the tension on the individual blades.

The device of the present invention has a frame which can conveniently be made in the form of a flat plate that has parts adjacent its bottom edge that are adapted to straddle any one of the closely spaced blades in a bread slicing machine and to enter the spaces between any such blade and adjacent blades.

One of the blade engaging parts has blade engaging members that contact one face of the blade adjacent opposite ends of the bottom edge of the frame, and the other engaging part is in the form of a spring actuated lever that applies pressure to the opposite side of the blade between the spaced blade engaging members. The spring actuating means is adjustable to provide the desired pressure on the blade, and the pressure applying lever is connected to a pointer that moves over a dial on the instrument frame that is in a plane parallel to the blade. The movement of the pointer is proportionate to the deflection of the blade due to the pressure applied by the lever and serves to indicate the tension on the blade. By thus testing the tension on the individual blades, adjustment of the blade supports to apply uniform tension to the blade is facilitated.

The invention has for its object to provide an instrument of light weight which is of simple construction and relatively inexpensive and which can be quickly and easily applied to an individual blade in a bread slicing machine to ascertain the tensions to which the blade is subjected.

Reference should be had to the accompanying drawings forming a part of this specification, in which:

Figure 1 is a front elevation of a tensiometer embodying the invention;

Fig. 2 is a section on an enlarged scale taken as indicated by the line 2—2 in Fig. 1;

Fig. 3 is a section on an enlarged scale taken as indicated by the line 3—3 in Fig. 1; and

Fig. 4 is a section on an enlarged scale taken as indicated by the line 4—4 in Fig. 1.

The device of the present invention is an instrument of a size such that it can be readily carried in one hand and applied to the exposed portions of the flexible slicer blades of a bread slicing machine. The instrument of the present invention has a supporting frame which may be in the form of a flat plate 1 that has an elongated bottom edge 2 and an upright extension 3, that is narrower than the bottom portion of the plate to provide a convenient hand grip, and that is disposed at an acute angle to the bottom edge 2. The plate 1 may be in the form of a casting and provided with a marginal flange 4 which extends throughout the margin of the plate except at the bottom edge thereof. At opposite ends of the bottom edge the plate has integral positioning members 5 that may be en-

2

largements of the marginal flange 4 and that are provided with blade engaging edge faces 6 disposed in a plane parallel to the plate 1.

A pair of spaced bearing brackets 7 are attached to the front face of the plate 1 by means of screws 8, and these brackets receive between them a lever 9 that is disposed in a plane at right angles to the bottom 2 and substantially midway between the positioning members 5. A transverse pivot pin 10 extends through the lever 9 and is rigidly attached thereto, the ends of the pin being journaled in the brackets 7, and ball bearings 11 being interposed between the pivot pin 10 and the bearing brackets 7. The lever 9 has a downwardly extending blade engaging arm 12 that has a curved blade engaging face 13 for applying pressure to the front face of a slicer blade positioned against the faces 6 of the positioning members 5. The lever 9 also has an upwardly extending actuating arm 14 that is provided with an inclined cam face 15 at its upper end. The cam face 15 of the lever 9 engages with a roller 16 that is rotatably supported on an arm 17 extending laterally from a swingable member 18 rotatably mounted on a fixed pivot 19 having its axis disposed perpendicular to the plate 1 a short distance to one side of the plane of movement of the lever arm 14. An anti-friction ball bearing 20 is interposed between the member 18 and the pivot pin 19. The pivot pin 19 has a head 21 at its outer end that retains the member 18, and the inner end of the pin 19 is detachably secured in a boss 22 formed integrally with the plate 1 by means of a set screw 23. A light spring 24 attached at its upper end to the outer end of the arm 17 and at its lower end to one of the bearing brackets 7 serves to hold the roller 16 in engagement with the cam face 15 of the actuating lever. A pointer 25 is attached to the swingable member 18 and extends upwardly therefrom, the upper end of the pointer overlying an arcuate graduated dial 26 that is carried by the upright extension 3 of the supporting plate 1.

Means are provided for applying an outward thrust to the actuating arm 14 of the lever 9 which causes the blade engaging arm 12 to press inwardly against the front face of a band blade extending across the space between the positioning members 5. As herein shown, pressure is applied to the lever 9 by means of a plunger 27 that engages the rear face of the lever 9 above the pivot 10 and that is actuated by a compression spring 28 mounted in a screw threaded barrel 29, the barrel 29 being in turn screwed into a boss 30 formed integrally with the plate 1. The barrel 29 and plunger 27 are preferably disposed perpendicular to the plate 1, and the plunger 27 is slidably mounted in a screw plug 31 in the forward end of the barrel 29. The spring 28 is interposed between the plunger 27 and an adjustable plug 32 screwed into the rear end of the barrel 29. By adjusting the plug 32 the tension of the spring 28 may be varied to apply the desired pressure to the lever 9.

The upper end of the lever 9 may be provided with a knob 33 that can be conveniently engaged by the thumb of the hand gripping the supporting plate 1 to press the upper end of the lever toward the plate and move the blade engaging arm 12 outwardly away from the plate to permit the slicer blade to be straddled by the driver arm 12 and the blade positioning members 5. Upon release of the thumbpiece 33 the blade engaging arm 12 will be moved into engagement with the outer face of the blade straddled by the instrument, and pressure applied to the blade by the arm 12 will cause the blade to be deflected toward the face of the plate 1. The amount of deflection of the blade is a function of the blade tension and becomes greater as the tension on the blade is lessened so that the amount of deflection imparted to the blade by the actuating lever indicates the tension to which the blade

is subjected. The movement transmitted to the pointer by the actuating lever is proportional to the amount of deflection of the blade, and the dial 26 may be calibrated to indicate tension on the blade.

By applying the tensiometer to the individual blades in a bread slicing machine, any inequalities in tension become readily apparent, and the adjustment of the blade supports necessary to apply uniform tension is thereby facilitated.

It is to be understood that in accordance with the provisions of the patent statutes, variations and modifications of the specific devices herein shown and described may be made without departing from the spirit of the invention.

What I claim is:

1. A tensiometer for measuring the tension of a flat flexible blade comprising a plate having positioning members projecting from its front face adjacent opposite ends of its bottom edge and having edge faces substantially parallel to said plate for engagement with one face of a blade, a lever mounted on said plate to swing about an axis substantially parallel to said plate, said lever having a downwardly extending arm engageable with the opposite face of a blade engaging said positioning members and having an upwardly extending arm provided with a cam face at its upper end, a pivot pin carried by said plate and projecting from its front face laterally of the upper end of said lever, a swingable member mounted to turn on said pivot and having a laterally extending arm engaging said cam face, a dial carried by said plate above said pivot pin, and a pointer attached to said swingable member and movable over said dial.

2. A tensiometer for measuring the tension in a flat flexible blade, comprising a frame plate having at least one blade positioning member projecting outwardly from one side face of the plate, a lever disposed outwardly from said plate side face and pivotally mounted on said plate to swing an arm of said lever toward and away from said plate about an axis substantially parallel to said side face, there being at least one blade engaging face on said arm of said lever and one blade engaging face on each said positioning means, and there being three such blade engaging faces which are disposed in planes that are substantially parallel to said plate side face, two of said blade engaging faces being spaced apart in a direction parallel to said axis and facing in one direction and being fixed relative to each other for engaging one side of a blade extending parallel to said plate side face, and the third of said blade engaging faces facing substantially in the opposite direction for engaging the opposite side of said blade at a point between the points of contact of said two relatively fixed blade-engaging surfaces, spring means acting between said plate and said lever to urge said two relatively fixed blade-engaging surfaces against one side of said blade and said third blade engaging surface against the opposite side thereof, and indicator means operatively connected to said lever for indicating the amount of deflection of a blade so engaged by said blade engaging faces, said indicator means comprising a cam surface on said lever, an indicator needle pivotally mounted on an axis normal to said plate side face for swinging movement over said plate side face, and a cam engaging said cam surface and operatively connected to said needle for swinging the same in response to pivotal movement of said lever.

engaging said cam surface and operatively connected to said needle for swinging the same in response to pivotal movement of said lever.

3. A tensiometer for measuring the tension of a flat flexible blade, comprising a frame plate having spaced positioning members projecting outwardly from one side face of the plate, said positioning members having blade-engaging faces lying in a common plane substantially parallel to said plate side face for engaging one side face of a blade, a lever disposed outwardly from said plate side face and pivotally mounted on said plate to swing about an axis substantially parallel to said plane, an arm of said lever being swingable between said positioning members along a path normal to and cutting across the common plane of the blade engaging faces thereof, spring means for urging said arm of said lever against the opposite side face of a blade engaged on one side face by the blade-engaging faces of said positioning members, and indicator means operatively connected to said lever for indicating the amount of deflection of a blade between said positioning members when so engaged by said lever arm and positioning members, said indicator means comprising a cam surface on said lever, an indicator needle pivotally mounted on an axis normal to said plate side face for swinging movement over said plate side face, and a cam engaging said cam surface and operatively connected to said needle for swinging the same in response to pivotal movement of said lever.

4. A tensiometer for measuring the tension of a flat flexible blade, comprising a frame plate having spaced positioning members projecting outwardly from one side face of the plate, said positioning members having blade-engaging faces directed away from said plate side face and lying in a common plane substantially parallel thereto for engaging one side face of a blade, a lever disposed outwardly from said plate side face and pivotally mounted on said plate to swing about an axis substantially parallel to said plane, an arm of said lever being swingable between said positioning members along a path normal to and cutting across the common plane of the blade engaging faces thereof, spring means for urging said arm of said lever in the direction of said plate and against the opposite side face of a blade engaged on one side face by the blade engaging faces of said positioning members, and indicator means operatively connected to said lever for indicating the amount of deflection of a blade between said positioning members when so engaged by said lever arm and positioning members, said indicator means comprising a cam surface on said lever, and indicator needle pivotally mounted on an axis normal to said plate side face for swinging movement over said plate side face, and a cam engaging said cam surface and operatively connected to said needle for swinging the same in response to pivotal movement of said lever.
